DESIGN FOR A BOTTLE CARRIER

Arthur H. Edgerton, Cleveland, Ohio, assignor to Convenient Carrier Corporation, Cleveland,
Ohio, a corporation of Ohio

Application November 9, 1944, Serial No. 116,255

Term of patent 14 years

(Cl. D58—4)

To all whom it may concern:

Be it known that I, Arthur H. Edgerton, a citizen of the United States, residing at Cleveland, in the county of Cuyahoga and State of Ohio, have invented a new, original, and ornamental Design for a Bottle Carrier, of which the following is a specification, reference being had to the accompanying drawing, forming a part thereof.

In the drawing:

Fig. 1 is a plan view;

Fig. 2 is an end elevation; and

Fig. 3 is a side elevation of a bottle carrier showing my design.

I claim:

The ornamental design for a bottle carrier, substantially as shown.
